HANGAR FOR DIRIGIBLES

Filed June 22, 1929

FIG. 1.

FIG. 2.

Inventor
Charles J. Carlotti

By his Attorney

C. J. Carlotti

UNITED STATES PATENT OFFICE

CHARLES J. CARLOTTI, OF NEW YORK, N. Y.

HANGAR FOR DIRIGIBLES

Application filed June 22, 1929. Serial No. 372,857.

This invention relates to improvements in hangars for dirigibles, and more particularly to a hangar constructed entirely below the surface of the ground.

5

Objects

An object of the invention is to provide an improved sub-surface hangar for dirigibles with means for aligning with and housing a dirigible in the hangar.

10 A further object of the invention is to provide an improved sub-surface hangar for dirigibles, which will be equipped with longitudinally extending, transversely slidable trussed roof sections capable of being moved to uncover the hangar when a dirigible is being placed therein or being removed therefrom, and of being brought together to cover the hangar when desired, thereby protecting

15 the hangar and dirigible housed therein from the elements such as rain, wind and lightning.

20 Other objects will appear as the description proceeds.

25

Drawings

In the accompanying drawings which form a part of my application,

25 Figure 1 is a longitudinal sectional view of my improved dirigible hangar, showing a dirigible attached to the mooring mast and overlying the hangar.

30 Figure 2 is a plan view of the hangar, showing a dirigible about to be placed within, and showing in dotted lines the actual position of the dirigible when housed in the hangar, and

35 Figure 3 is a transverse sectional view of the hangar, showing a dirigible in dotted lines within the same, and the relative positions of the slidable trussed roof sections.

40 Like characters of reference are used throughout the following specification and the accompanying drawings to designate corresponding parts.

Description

45 It is a well known fact that almost all hangars employed today are built above the surface of the ground, and hence, are sub-

ject to high winds, rain and lightning, which often demolish the hangars and destroy the expensive dirigible housed therein. It is, therefore, a decided step in advance to construct a hangar for dirigibles below the surface of the ground, where a dirigible may be stored and housed with a maximum of safety, and ease in placing the dirigible within the hangar, or removing the same therefrom.

55 In constructing my improved form of hangar, I excavate an elongated hole in the earth which will be considerably longer and wider than the length and width of the largest dirigible to be housed in the hangar. At each side of the opening, I also excavate several feet in depth from the sides of the opening to a distance of approximately the width of the hangar per se, which shallower excavations will extend the full length of the hangar, and will accommodate the transversely slidable trussed roof sections.

60 The side walls and floor of the hangar and the floor and walls of the laterally extending excavations will then be covered by a strong, relatively thick coating of reinforced cement 1, as clearly shown in the drawings.

65 A telescoping mooring mast 2 will be positioned within the hangar at one end thereof, and may be extended well above the surface of the ground when desired, or may be moved together to be completely received within the vertical limits of the hangar, and is provided with the usual form of connecting mechanism for securing the nose 3 of a dirigible 4, thereto.

70 A plurality of winches 5 will be positioned at the opposite sides of the hangar, on the floor thereof, and on the surface of the ground, and are provided with cables 6 for connecting with the dirigible and to assist in aligning the same above the hangar.

75 A pair of longitudinally extending, transversely slidable trussed roof sections 7 are mounted in the shallow excavations at the opposite sides of the hangar, and are adapted to completely cover the hangar when closed, and may be moved to completely uncover the hangar when it is desired to place a dirigible therein, or remove a housed dirigible.

therefrom. A stairway 8 will be positioned near a wall of the hangar to permit ready access to and from the same.

Many minor changes in detail or construction may be resorted to without departure from the spirit of the invention.

Having thus described my invention what I claim as new and desire to secure by Letters Patent of the United States is:

- 10 A sub-surface hangar as characterized comprising in combination, a plurality of flatwise slideable truss roof sections, a telescopic mooring mast extending up beyond the top of the hangar when in use, connecting mechanism on the upper end of said telescopic mooring mast for securing an end of a dirigible thereto, a plurality of winches on the bottom of the hangar, and on the ground above the hangar, cables on said 15 winches for engaging the dirigible thereto, whereby the dirigible may be lowered into the hangar and the mooring mast collapsed simultaneously with the winches in operation, and the plurality of said flatwise slideable truss roof sections brought inwardly 20 towards each other to close the hangar when the dirigible is housed therein.
